United States Patent

Des. 238,775
Patented Feb. 10, 1976

238,775

WHEEL COVER

Norman Earl Whittinger, 2117 S. Fawn Drive,
Spokane, Wash. 99206

Filed Jan. 6, 1975, Ser. No. 538,761

Term of patent 14 years

Int. Cl. D12—16

U.S. Cl. D12—212

FIG. 1

FIG. 2

FIG. 3

FIG. 4

FIG. 1 is a perspective view of a wheel cover showing my new design;

FIG. 2 is an enlarged front elevational view thereof;

FIG. 3 is a greatly enlarged fragmentary sectional view thereof taken along line 3—3 in FIG. 2; and

FIG. 4 is an enlarged side elevational view thereof.

I claim:

The ornamental design for a wheel cover, as shown.
